(57) **CLAIM**

The ornamental design for a sheet good with surface pattern, as shown and described.

DESCRIPTION

The sole FIGURE is a plan view of a sheet good with surface pattern showing our new design.

The broken lines shown along the border of the FIGURE depict the boundaries of the sheet good with surface pattern and indicate that a specific length and width forms no part of the claimed design and that the pattern repeats uniformly throughout the length and width of the sheet good with surface pattern. The broken lines form no part of the claimed design.
